UNITED STATES PATENT OFFICE

90,475

DESIGN FOR A FLEXIBLE POCKET RECEPTACLE

Warner R. Buxton, Longmeadow, Mass.

Application May 17, 1933. Serial No. 48,153

Term of patent 14 years

To all whom it may concern:

Be it known that I, WARNER R. BUXTON, a citizen of the United States, residing at Longmeadow, in the county of Hampden and State of Massachusetts, have invented a new, original, and ornamental Design for Flexible Pocket Receptacle, of which the following is a specification, reference being had to the accompanying drawing, forming part thereof.

Fig. 1 is an elevational view of an open bill fold showing the inner face thereof in which is embodied my new design; and

Fig. 2 is a top plan view of the bill fold.

The design appears wholly on the inner face of the bill fold shown in Fig. 1 and its characteristic feature lies in the lines which produce the appearance of a conventionalized tulip.

I claim:

The ornamental design for a flexible pocket receptacle substantially as shown and described.

WARNER R. BUXTON.
